UNITED STATES PATENT OFFICE.

WILLIAM NESS, OF CARRYVILLE, WISCONSIN.

FOLDING BOX.

1,346,839.

Specification of Letters Patent. Patented July 20, 1920.

Application filed August 9, 1918. Serial No. 249,069.

To all whom it may concern:

Be it known that I, WILLIAM NESS, a citizen of the United States, residing at Carryville, in the county of Dunn and State of Wisconsin, have invented certain new and useful Improvements in Folding Boxes; and I do hereby declare the following to be a full, clear, and exact description of the invention, such as will enable others skilled in the art to which it appertains to make and use the same.

This invention relates to improvements in folding boxes and has for one of its objects the provision of a device of this character, whereby the side and end walls can be readily folded inwardly over the bottom wall and the cover then placed over the bottom wall so as to hold the sides and end walls in a folded position providing a very compact device when in a folded position and one which will not require a considerable space when in storage.

Another object of this invention is the provision of angularly related ends upon the side walls adapted to engage the end walls when in an unfolded position to prevent the end walls from being swung or moved outwardly during the use of the box.

A further object of this invention is the provision of means for detachably connecting the side and end walls so that they will retain an upright position while in use or while removing or replacing the contents of the box.

A still further object of this invention is the provision of a folding box of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description, and accompanying drawing, in which:—

Figure 1 is a perspective view of a folding box constructed in accordance with my invention,

Fig. 2 is a longitudinal sectional view of the same,

55

Fig. 3 is a transverse sectional view illustrating the means of detachably securing the end walls to the side walls.

Fig. 4 is a fragmentary perspective view of the box in a folded position with the cover 60 removed,

Fig. 5 is a detail sectional view of the same, and

Fig. 6 is a fragmentary perspective view of a modified form of means connecting the 65 end walls to the side walls.

Fig. 7 is a fragmentary perspective view of another modified form of means of connecting the end walls to the side walls.

Referring in detail to the drawing, the numeral 1 indicates as an entirety a box which may be constructed of metal or any other material suitable for the purpose and consists of a bottom wall 2 having its longitudinal edges bent and disposed vertically to 75 form attaching flanges 3 which have their edges slit and rolled to form hinge barrels 4. Side walls 5 have their lower longitudinal edges slit and rolled to form barrels 6 that are alined with the barrels 4 to receive pintles 80 7 for hingedly connecting the side walls 5 to the bottom 2.

End walls 8 have their lower ends hinged to the flanges 3 as illustrated at 9 adjacent the ends of the bottom wall 2 and the end walls 8 85 are of greater height than the side walls 5 so that the upper edges of the side and end walls are in alinement with each other. The end walls 8 are of a greater height than the side walls 5, and are folded inwardly over 90 the bottom 2 and the side walls 5 are folded inwardly over the end walls to provide a compact article.

The ends of the side walls 5 have formed thereon angularly related flanges 10 that are 95 adapted to engage the end walls 8 to prevent said end walls 8 from swinging outwardly when in vertical or operative position. Resilient arms 11 are secured to the end walls as illustrated at 12 and have their ends bent 100 to form hooks 13 that are adapted to engage over the upper edges of the side walls 5 for holding the side and end walls together when in box forming position. If desired, the arms 11 may be substituted by members 14 105 as illustrated in Fig. 6 which have formed

thereon extensions 15 provided with eyes to receive a suitable pin (not shown) for holding the side and end walls together.

The end walls may also have secured thereon 5 to hooks 19 adapted to have their bill portions disposed over the side walls for retaining the walls in engagement or in box formation.

A top or cover 16 has formed thereon 10 downwardly depending flanges 17 that engage the side and end walls. The side flanges are provided with offset portions 18 to receive the hooks 13 of the arms 11 when the cover is applied to the side and end walls. 15 From the foregoing description, taken in connection with the accompanying drawing, it will be noted that a device has been provided which can be used for numerous purposes, such as containing cigars, candy, or 20 merchandise articles and which can be readily folded into a compact article when desired.

While I have shown and described the preferred embodiment of my invention, it will 25 be understood that minor changes in construction, combination and arrangement of

parts may be made without departing from the spirit and scope of the invention, as claimed.

What I claim as new is:— 30

A folding box comprising a bottom wall, side and end walls hinged to the bottom wall, flanges on the ends of the side walls and overlying portions of the outer faces of the end walls, apertured lugs formed on the end walls 35 adjacent their upper edges, rods extending through the lugs and having their ends bent to form hooks to engage the upper edges of the side walls, a cover resting on the side and end walls, flanges formed on the cover 40 and engaging the outer faces of the side and end walls, and offset portions formed on some of said last named flanges and receiving the hooks for preventing lateral movement of the rods and adapted to aid in holding the 45 cover on the side and end walls.

In testimony whereof I affix my signature in presence of two witnesses.

WILLIAM NESS.
